UNITED STATES PATENT OFFICE.

STEPHEN D. BAKER, OF NEW YORK, N. Y.

DESIGN FOR A TOWEL-BAR.

53,191.

Specification for Design.

Patented Apr. 15, 1919.

Application filed February 3, 1917. Serial No. 146,533. Term of patent 14 years.

To all whom it may concern:

Be it known that I, STEPHEN D. BAKER, a citizen of the United States, residing at New York city, in the county of New York and State of New York, have invented a new, original, and ornamental Design for a Towel-Bar, of which the following is a specification, reference being had to the accompanying drawing, forming part thereof.

The drawing shows in Figure 1 a front perspective view of my new design, and in Fig. 2 a plan view of one of the posts, with the projecting portion thereof in section.

I claim:

The new and ornamental design for a towel bar, substantially as herein shown.

In testimony whereof, I affix my signature.

STEPHEN D. BAKER.
